UNITED STATES PATENT OFFICE.

LOUIS F. MILLER, OF NEW HAVEN, CONNECTICUT.

DESIGN FOR A PUZZLE-BOX.

SPECIFICATION forming part of Design No. 26,910, dated April 13, 1897.

Application filed February 15, 1897. Serial No. 623,573. Term of patent 7 years.

To all whom it may concern:

Be it known that I, LOUIS F. MILLER, of New Haven, in the county of New Haven and State of Connecticut, have invented a new 5 Design for Puzzle-Boxes; and I do hereby declare the following, when taken in connection with the accompanying drawing and the letters of reference marked thereon, to be a full, clear, and exact description of the same, 10 and which said drawing constitutes part of this specification and represents a perspective view of a box constructed in accordance with my invention.

This invention relates to a design for a puzzle-box; and the design consists in the configuration shown in the accompanying illustration and hereinafter described.

As shown in the drawing, the shape of the box A is tetragonal. In the bottom B of the box are seats C, around each of which is a circular ring differentiated in size and, if desired, in color from each other and the surface of the box.

I claim—

The design for a puzzle-box, as herein shown 25 and described.

In testimony whereof I have signed this specification in the presence of two subscribing witnesses.

LOUIS F. MILLER.
